G. W. WARMOTH.
ANCHOR STRIP FOR PAVING BLOCKS.
APPLICATION FILED AUG. 16, 1915.

1,226,149.

Patented May 15, 1917.

UNITED STATES PATENT OFFICE.

GEORGE W. WARMOTH, OF INDIANAPOLIS, INDIANA.

ANCHOR-STRIP FOR PAVING-BLOCKS.

1,226,149.

Specification of Letters Patent. Patented May 15, 1917.

Application filed August 16, 1915. Serial No. 45,722.

To all whom it may concern:

Be it known that I, GEORGE W. WARMOTH, a citizen of the United States, and a resident of Indianapolis, county of Marion, and 5 State of Indiana, have invented a certain new and useful Anchor-Strip for Paving-Blocks; and I do hereby declare that the following is a full, clear, and exact description thereof, reference being had to the accompanying drawings, in which like letters refer to like parts.

The object of this invention is to provide an anchor strip for paving blocks which is adapted to be used between street railway 15 tracks or adjacent thereto. The anchor plate is composed of a thin metal strip having its ends turned so as to fit snugly between the rails. There are a plurality of cold punched holes leaving a jagged surface 20 which may be forced into paving blocks so that they are gripped thereby and held in place. The anchor strip is placed between each row of blocks so that it engages the blocks on either side and retains them in 25 position. This may also be accomplished when used with paving bricks by providing a hole in the anchor through which a rod 30 may be inserted and passed through a similar hole in the bricks.

The main object of this invention is to overcome the turning up of paving blocks between the adjacent street railway tracks, thereby avoiding the necessity of relaying 35 them from time to time. Also by providing a similar anchor strip on the outside of the rails and adjacent thereto, the blocks near the outside of the rails are prevented from being displaced.

The full nature of the invention will be 40 understood from the accompanying drawings and the following description and claims.

In the drawings, Figure 1 is a plan view showing the paving blocks between the 45 tracks. Fig. 2 is a cross section on the line 2—2 of Fig. 1. Fig. 3 is a perspective view of the anchor plate. Fig. 4 is a cross section on the line 4—4 of Fig. 2. Fig. 5 is a modified view showing the anchor plate 50 adapted to be used with bricks. Fig. 6 is a perspective view of the exterior anchor plate.

In the drawings, there are tracks 10 and 55 paving blocks 11. Between each row of the paving blocks there is a metal strip or an-

chor strip 12 having its ends bent at right angles so as to form flanges 13 and adapted to fit snugly against the webs of the rails.

In the drawings holes 14 are shown which are cold punched so as to leave jagged edges 60 and which are so arranged that the jagged edges of every other hole protrude from one side of the anchor strip, while those of every other hole protrude on the other side thereof. In addition to said holes there are angular 65 cuts made in the metal with the points bent at right-angles thereto to form the projections 15. However, this invention is not restricted to this means of gripping the blocks, but any other rough or sharp surface may be 70 used, as desired.

There is a body of concrete 16 and also a layer of sand 17 upon which the blocks rest. It is necessary that said strip engage the shoulder and base of the rail so as to be 75 held firmly therein.

In laying the blocks a row is placed in position and properly tamped and then the anchor strip is placed adjacent to the row of blocks and another row placed in position 80 on the other side of said strip. The blocks are then hammered or clamped together against said strip so that the points 15 and the jagged edges of the holes 14 will enter the blocks and hold them firmly. This 85 process is continued in filling along the whole length of the track. It then becomes impossible for the blocks to escape from their position and it will be impossible for them to escape from place because of their 90 expansion and the heavy traffic over them.

This same result may be accomplished when bricks are used by providing a hole 18 in the anchor strip and a similar hole 19 in the brick through which a rod or bar 20 95 may be inserted so as to hold the bricks in position.

For preventing the bricks on the outside of the tracks and adjacent thereto from being displaced, there is a plate 22 adapted to 100 grip the blocks in the same manner as the plate 12. This plate tapers outwardly and has means 23 on the end thereof for anchoring it to the foundation.

The invention claimed is:

1. In the combination with street railway tracks, of paving blocks laid between said tracks, a metal strip between each row of said blocks, means for engaging said blocks and holding them in their proper position, 110

2
and means on each end of said strip for securing it in position.

2. In the combination with street railway tracks, of paving blocks laid between said tracks, a metal strip between each row of said blocks, means on said strip for engaging said blocks and holding them in their proper position, and flanges on each end of said strip adapted to fit snugly under the lip

of said rails so as to be held securely in position by the head thereon.

In witness whereof I have hereunto affixed my signature in the presence of the witnesses herein named.

GEORGE W. WARMOTH.
